GAME BOARD

Byron L. La Goy, 5121½ Brighton Ave.,
San Diego, Calif. 92107

Filed Mar. 12, 1970, Ser. No. 21,878

Term of patent 14 years

Int. Cl. D21—01

U.S. Cl. D34—5

The sole figure is a top plan view of a game board showing my new design. Said game board is of conventional thickness.

I claim:

The ornamental design for a game board, as shown and described.
